INVENTOR

JOHN BYROM

John G. Wright
ATTORNEY

UNITED STATES PATENT OFFICE.

JOHN BYROM, OF LIVERPOOL, ENGLAND.

VIOLIN, VIOLA, AND VIOLONCELLO PEG.

1,362,391.

Specification of Letters Patent. Patented Dec. 14, 1920.

Application filed February 21, 1920. Serial No. 360,270.

To all whom it may concern:

Be it known that I, JOHN BYROM, a subject of the King of Great Britain, and a resident of Liverpool, England, have invented certain new and useful Improvements in Violin, Viola, and Violoncello Pegs, of which the following is a specification.

This invention relates to violin, viola, and violoncello tuning pegs of the kind having a tapered portion fitting within the tapered bore of a bushing fixed within the peg hole of the peg box. Where means have been previously provided for adjusting the tightness of such peg in the bushing, there has been a tendency to impose stress upon the walls of the peg box owing to the fact that the pressure due to the adjustment is transmitted to the side of the peg box remote 20 from the peghead. The chief object of this invention is to eliminate such side stress.

According to this invention, the tuning peg is so constructed and arranged that the pressure arising from tightening the peg in the bushing is entirely taken up between the bushing and the peg itself so that all side stress is removed from the head of the instrument. For this purpose, the bushing may be tapered internally so that its bore decreases in diameter toward the peghead end thereof and the peghead which can be caused to slide on the peg but cannot turn relatively thereto may be pressed against the outer end of the bushing by 30 means of a milled nut or other analogous element screwed upon the end of the peg. By this means, the tightness of the peg in the bushing may be adjusted. The peghead may be detachable and has a slotted end engaging a cross pin or tommy carried in the peg. In order to obtain metal-to-fiber frictional contact surfaces between the peg and the bushing, the latter may be of fiber or of metal lined with fiber and the peg 40 may be made of metal or metal covered with fiber.

The invention is illustrated in the accompanying drawings, in which Figure 1. is an elevation of a violin head showing the peg box and one peg fitted in accordance with this invention, Fig. 2. is a side view of Fig. 1. Fig. 3. is a longitudinal section through a peg showing the bushing and peg box wall, and detachable peg head. Fig. 4. is an end 55 view of the peg head showing the internal slotting, and Fig. 5. is a detailed view of the

peg itself, showing the tapered portion and the cross pin or tommy by means of which the peg is turned.

In carrying out the invention, a bushing 60 1 is fitted by gluing or otherwise into the side wall 2 of the peg box 3, of the instrument. This bushing is of fiber though if desired it may be made of metal, either entirely or with a fiber lining, and is preferably slightly tapered on its exterior as shown. The interior of the bushing 1 is also tapered, the bore diminishing in diameter from the inner end at the peg box to the outer end. This tapered bore forms a bearing 70 for a correspondingly tapered part 4^a of the peg proper 4 which is of metal and rotates within the bushing 1. The part of the peg 4 which enters the peg box 3 may be made cylindrical, as shown, or tapered, 75 and is drilled with the usual hole 5 for the string. The further end 6 of the peg is reduced where it turns in the bore of a plug 7 fitted into the small peg hole in the opposite wall of the peg box. The smaller end 80 of the tapered part 4^a of the peg terminates in a screwed stem 4^b over which fits the head 8 of the peg, and is retained in position by a milled nut 9, terminal screw or other analogous element. The peg head 8 is bored 85 8^a to pass over the screwed stem 4^b of the peg, and shaped at 8^b to fit the smaller end of the tapered part 4^a and is also internally slotted at 10, such slot engaging a tommy 90 or cross pin 11 which passes transversely through an aperture in the peg so that as the peg head 8 is turned the peg 4 rotates in the bushing 1. It will be seen that by adjusting the milled nut 9 or the like, the tightness of the fit of the tapered part 4^a in 95 the bushing 1 may be regulated as desired, the frictional resistance to turning of the peg in the bushing being determined by the wedging pressure of the tapered part 4^a in the bushing, and by the pressure of the 100 peg head 8 where it abuts against the end of the bushing 1.

The bushing 1 is preferably made of vulcanized fiber, but it may be entirely of metal or of metal with a fiber or vulcanized lining, as found convenient, or, the bushing may be of metal and the peg of metal with a lining or bushing of fiber or vulcanite, if desired. The bushing 1 being glued into the larger hole of the peg box forms in 110 appearance the equivalent of the usual shank of the ordinary type of peg, thus

maintaining the usual appearance of the pegs.

If desired, the tommy or cross pin 11 may take the form of a flat piece passed through 5 a slot in the peg, or in place of such a cross pin the end of the tapered part 4^a may be flattened or otherwise formed to enable the peg head 8 effectively to turn the peg.

With such an arrangement the frictional 10 resistance of the peg to turning in the bushing may be graduated to any nicety and to suit the particular requirement of the player, while, owing to the tapered configuration of the peg in the bushing and 15 the great length of the bearing, the retention of the peg against backward turning is quite marked, thus enabling the peg to be used for tuning with the instrument in a playing position.

20 While the bushing has been described as of fiber it may be made of other suitable material such as rubber, papier mâché, metal, or even wood.

Where means have been previously provided for adjusting the tightness of a peg 25 in the peg box, such means have resulted in a strain being set up in the walls of the peg box owing to the fact that the whole peg was pulled by the adjustment transversely

into the peg box. Such a side strain on the 30 violin head is absolutely eliminated by this invention the pressure arising from the adjustment being self contained as between the peg and the bushing, thus entirely removing all strain from the head of the instrument. 35

I claim—

In a stringed musical instrument including a peg box, a tuning peg therefor comprising a bushing fixed in the peg box, said bushing having a bore therein tapering toward the peg head end thereof, a peg fitting into said bushing and tapered to correspond to the tapered bore thereof, a head movable longitudinally and non-rotatably on said 40 peg, said head being in constant engagement with said bushing, and means for causing pressure of the head against the bushing, to thereby cause frictional engagement between the peg and bushing throughout their full length. 45

In testimony whereof I affix my signature in presence of two witnesses.

JOHN BYROM.
